(57) CLAIM

(63) Continuation-in-part of application No. 29/106,487, filed on
Jun. 16, 1999, now Pat. No. Des. 421,527, which is a
continuation-in-part of application No. 29/091,814, filed on
Aug. 6, 1998, now abandoned, which is a continuation-in-
part of application No. 29/082,956, filed on Feb. 2, 1998,
now abandoned.

The ornamental design for paper product, as shown and
described.

DESCRIPTION

(51) LOC (7) Cl. **05-06**

FIG. 1 is a top front perspective view of a paper product,
showing our new ornamental design.

(52) U.S. Cl. **D5/53; D5/55; D5/60;**
D5/61

FIG. 2 is a top plan view of the paper product shown in FIG.
1, the opposite (bottom) side view being a mirror image
thereof.

(58) Field of Search **D5/47, 49, 52,
D5/53, 54, 56, 60, 99; 162/140; 428/35.6,
43, 44, 98, 141, 182, 187, 198, 542.6, 904.4**

FIG. 3 is a frontal elevational view of the paper product
shown in FIGS. 1 and 2; and,

(56) **References Cited**

FIG. 4 is a side elevational view of the paper product shown
in FIGS. 1, 2 and 3, the opposite side elevational view being
a mirror image thereof.

U.S. PATENT DOCUMENTS

D. 33,013 7/1900 Migel .
D. 38,948 * 12/1907 Landenberger D5/49
D. 49,842 11/1916 Chace .
D. 61,577 * 10/1922 Leiper D5/49
D. 62,468 * 6/1923 Boyd et al. D5/49

D. 75,536 6/1928 Vrooman .
D. 97,932 12/1935 George .

It is to be understood that the design pattern shown in FIGS.
1-4 continues uniformly throughout the length and width of
the paper product. The paper product is shown broken away
to indicate that the paper product has indeterminate width.
The broken lines are for illustrative purposes only and form
no part of the claimed design.
